UNITED STATES PATENT OFFICE.

MONROE KOCH, OF NEW YORK, N. Y.

DESIGN FOR A BODY FOR BELTS OR SIMILAR ARTICLES.

SPECIFICATION forming part of Design No. 32,301, dated February 27, 1900.

Application filed February 5, 1900. Serial No. 4,149. Term of patent 7 years.

To all whom it may concern:

Be it known that I, MONROE KOCH, a citizen of the United States, residing at New York, borough of Manhattan, county of New York, 5 in the State of New York, have invented and produced a new and original Design for the Bodies of Belts or Similar Articles; and I do hereby declare the following to be a full, clear, and exact description of the invention.

10 The drawing is a face view of the said design.

The leading feature thereof consists of the ornamentation shown applied to the elongated belt-body A, (or body of a similar article,) 15 having its ends B reduced in width, the said ornamentation consisting of a group of transverse ribs C, diminishing in length from the middle outward in each direction, and the longitudinal ribs D, extending from the transverse ribs C at each end of the group toward 20 the body ends B. A collar is one of the other articles similar to a belt to which this design can be applied.

I claim—

The design for the body of a belt or similar 25 article, as shown and described.

In testimony whereof I affix my signature in presence of two witnesses.

MONROE KOCH.
